UNITED STATES PATENT OFFICE.

IRA VAUGHN, OF SALEM, AND FRANKLIN J. PERKINS, OF WOBURN, MASSACHUSETTS, ASSIGNORS TO THE VAUGHN MACHINE COMPANY, OF PORTLAND, MAINE.

STAKING-MACHINE.

SPECIFICATION forming part of Letters Patent No. 639,319, dated December 19, 1899.

Application filed May 12, 1899. Serial No. 716,535. (No model.)

To all whom it may concern:

Be it known that we, IRA VAUGHN, residing in Salem, in the county of Essex, and FRANKLIN J. PERKINS, residing in Woburn, in the county of Middlesex, State of Massachusetts, citizens of the United States, have invented 5 an Improvement in Staking - Machines, of which the following description, in connection with the accompanying drawings, is a specification, like letters and figures on the drawings representing like parts.

This invention relates to a machine for working hides, skins, or leather, and is especially designed and adapted for use as a 15 staking-machine.

The invention has for one of its objects to provide a simple, efficient, and compact machine which takes up a minimum amount of room and can therefore be utilized in factories in places where like machines as heretofore constructed and known to us cannot be set up and operated owing to their length.

Another feature of this invention consists in providing a staking-machine in which the 25 tool-carrying levers are positively opened and closed by a simple and efficient mechanism, as will be described.

These and other features of this invention will be pointed out in the claims at the end 30 of this specification.

Figure 1 is a side elevation of a machine embodying this invention; Fig. 2, an end elevation of the machine looking toward the left in Fig. 1, with parts in section; Fig. 3, 35 a modification on an enlarged scale, to be referred to; Fig. 4, an end elevation of the upper part of the machine looking toward the right in Fig. 1; Fig. 5, a sectional detail on the line 5, Fig. 1; Fig. 6, a sectional detail 40 on the line 6 6, Fig. 5; and Fig. 7, a sectional detail on the line 7 7, Fig. 2.

The framework of the machine herein shown comprises a base *a* and side uprights *b c*, separated from each other and having secured 45 to their front ends brackets *d e*, which support the two parts of a table *f*, connected at their front end by a breast beam or bar *g*. The side supports *b c* support in suitable 50 guideways *h* a movable support or carrier *i*, adapted to be reciprocated in the said guide-

ways, and having erected upon it at its opposite sides two uprights *j*, between which are pivotally mounted two tool-carrying levers or arms *2 3*, hereinafter referred to as the upper and lower arm or lever, respectively. 55

In accordance with this invention the tool-carrying levers *2 3* are positively opened and closed, which is effected, as herein shown, by a toggle mechanism comprising links *4 5 6*, pivotally connected at one end to the levers *2 3* and having their other ends connected by a pin *6*, joined by links *7* to one end of an upright lever *8*, mounted on a pivot-pin *9*, carried by depending brackets *10* of the carrier *i*. (See Fig. 4.) The pivot-pin *6* is supported by upright links *11* pivotally connected at their lower ends to a block or plate *70*, (see Figs. 5 and 6,) which is adjustably secured to the carrier *i* by a bolt *71*, extended through a slot *72* in the carrier, the head of the bolt moving between guiding ribs or lugs *73* on the under side of the carrier. The lever *8*, as shown in Fig. 1, is provided at its lower end with a stud or roller *12*, extended into a cam-slot *13* in a plate, casting, or piece *14*, (see dotted lines, Fig. 1, and full lines, Fig. 7,) attached to the end of a connecting-rod *15*, joining a stud or pin *16* on an arm *17*, depending from the carrier *i*, with a stud or pin *18* on a fly-wheel or disk *19*. The cam-plate *14* may be detachably secured to the end of the connecting-rod *15*, as by screws *20*. (Indicated by dotted lines, Fig. 1, and full lines, Fig. 7.) The disk or wheel *19*, in accordance 85 with this invention, is fast on a shaft *21*, having bearings in the framework at the front of the machine and below the table *f*, and the said shaft has fast on it a pulley *22*, connected by a belt *23* with a pulley *24* of the main or driving shaft *25*, located at the opposite end of the machine. By this construction and arrangement of parts the machine is materially shortened and is thereby made available for use in close quarters, where machines of this class as now 95 commonly constructed could not be used on account of their length; and, furthermore, a large number of machines embodying this invention may be set up and operated in a small-sized room, thereby economizing in 100

floor-space and increasing the capacity of the tannery for the work to which these machines are put.

The cam-slot 13 is made, as shown in the drawings, so as to positively move the lever 8 in opposite directions, and thereby positively open and close the front ends of the levers or arms 2 3, which ends are provided with suitable staking-tools, herein shown as a roll 30, 10 carried by the upper arm, and two blades 31 32, carried by the lower arm. The roll 30 may be of rubber and is journaled in brackets 33, attached to a slide-plate 34, movable in guides 35, attached to the under side of the lever 2. The slide-plate 34 may be moved 15 to adjust the roll relatively to the blades 31 32 by a screw 36.

In the operation of the machine herein shown the carrier *i* is reciprocated in the 20 guideways *h* by the disk 19 through the connecting-rod 15 and depending arm 17, and during the forward movement of the carrier in the direction indicated by arrow 200, Fig. 1, the cam-slot 13 opens the jaws or levers 2 25 3, and during the back stroke or movement of the carrier the said cam-slot closes the said jaws or levers to effect the staking of the leather. The positive closing of the jaws or levers by the cam-slot may be assisted by a 30 spring 40, which is compressed when the jaws or levers are opened and expands when they are closed.

In Fig. 1 we have represented the stud or roller 12 as attached to the lever 8 and the 35 cam-plate 14 to the connecting-rod; but this construction may be reversed, if desired, as shown in Fig. 3, wherein the cam-slot 13 is formed in a plate or enlargement of the lever 8, and the stud or roller 12 is carried by an 40 arm 45, attached to the connecting-rod 15.

The main shaft 25 may be driven in any 45 suitable or usual manner, but in the present instance is shown as provided with a friction driving mechanism comprising a pulley 50, loose on the shaft 25 and continuously driven by a belt. (Not shown.) The pulley 50 has co-operating with it a disk or pulley 51, keyed on the shaft 50 and movable thereon in opposite directions by a lever 52, pivoted at 53, and 50 having its upper end provided with a threaded opening, into which extends the threaded end of a shaft 54, provided with a gear 55, which is engaged by a segmental gear 56, attached to a lever 57, operated by a shipper-rod 58, extended toward the front of the machine and supported by a hanger or bracket 59, depending from the table *f*. (See Fig. 1.) The link 4 of the toggle mechanism is preferably made adjustable or extensible, so as 60 to accurately position the roll 30 with relation to the blades 31 32 when the levers 2 3 are in their closed position. The lower lever 3, as shown, has attached to it an auxiliary table or support 60 for the leather.

65 The lower jaw 3 may be adjusted so as to properly position the working tools 31 32 with relation to the table *f* by moving the block 70

longitudinally on the carrier, so that the perpendicular distance from the center pin 6 to the carrier may be varied, according to whether 70 it is desired to raise or lower the front end of the lower jaw-carrying lever 3. By moving the slide 70 backward or toward the left (viewing Fig. 1) on the table or carrier *i* the point 6 is lowered when the toggle is operated, so 75 that the two links 4 5 are straight. Then the point 6 is raised and the front end of the lever 3 is lowered. The slot 72 in the carrier *i* is made of sufficient length to enable the lower end of the links 11 to be carried forward a 80 sufficient distance to throw the center point 6 to the left of the vertical line when the toggle-links 4 5 are in their straightened position, which movement would elevate the front end of the lever 3. In this manner, by means 85 of the block 70, the tools carried by the lower jaw or lever 3 can be accurately positioned with relation to the table.

We claim—

1. In a machine of the class described, the 90 combination of the following instrumentalities, viz: a framework, a reciprocating carrier mounted thereon and provided with an arm depending from said carrier, tool-carrying arms carried by said carrier, a rotatable crank disk 95 or wheel located at the front end of the machine, a connecting-rod joining said disk or wheel with said depending arm, a main or driving shaft located at the rear of the said crank disk or wheel, and means to operate said 100 crank disk or wheel from said driving-shaft, for the purpose specified.

2. In a machine of the class described, the 105 combination of the following instrumentalities, viz: a reciprocating carrier, tool-carrying arms pivoted on said carrier, a rotatable disk or wheel, a connecting-rod joining the said disk or wheel to said carrier to produce reciprocation of the same, and means to positively open and close said tool-carrying arms 110 comprising a lever, toggle mechanism joining said lever to said tool-carrying arms, and a cam-slot and stud intermediate of said lever and connecting-rod and actuated by the latter to move the lever on its pivot and positively open and close the tool-carrying levers, 115 substantially as described.

3. In a machine of the class described, the 120 combination of the following instrumentalities, viz: a framework, a reciprocating carrier mounted thereon and provided with a depending arm, a rotatable disk or wheel connected to the depending arm of said carrier to reciprocate the same and located at one end of the machine, tool-carrying arms or levers pivoted 125 on said carrier, means to operate them, and a driving-shaft located at the end of the machine opposite to the said disk or wheel, and means to rotate said disk or wheel from said driving-shaft, substantially as and for the 130 purpose specified.

4. In a machine of the class described, the 135 combination of the following instrumentalities, viz: a framework provided with a table

- at its front end, a reciprocating carrier mounted on said framework, an arm depending from said carrier, a disk or wheel mounted on a shaft having bearings in the framework at the front end of the machine below said table, a connecting-rod joining said depending arm with said disk or wheel, tool-carrying levers or arms pivoted to said carrier, means actuated by said connecting-rod to operate said levers, a main or driving shaft having bearings in the framework at the rear of the shaft on which said disk or wheel is mounted, and means to connect the said shafts, for the purpose specified.
- 15 5. In a machine of the class described, the combination of the following instrumentalities, viz: a reciprocating carrier, tool-carrying arms pivoted on said carrier, toggle-levers connected to said arms, a block or piece adjustable on said carrier, a link connection between said block and the pivot of said toggle-levers, a cam to operate said toggle-levers and a disk or wheel to operate said cam, substantially as described.

6. In a machine of the class described, the combination of the following instrumentalities, viz: a reciprocating carrier, tool-carrying arms pivoted on said carrier, an arm depending from said carrier near its rear end, a rotatable disk or wheel located at the front end of the machine, a connecting-rod joining said depending arm with said disk or wheel, mechanism to close said arms, and an extension on the connecting-rod projecting toward the rear of the machine and beyond the point of attachment of said connecting-rod to the said depending arm and operatively connected to the mechanism which closes the said arms, substantially as described.

In testimony whereof we have signed our names to this specification in the presence of two subscribing witnesses.

IRA VAUGHN.
FRANKLIN J. PERKINS.
